UNITED STATES PATENT OFFICE.

ELLIOTT R. MOFFET, OF JOPLIN, MISSOURI.

APPARATUS FOR SMELTING AND CALCINING LEAD AND OTHER ORES.

SPECIFICATION forming part of Letters Patent No. 329,199, dated October 27, 1885.

Application filed June 30, 1885. Serial No. 170,254. (No model.)

To all whom it may concern:

Be it known that I, ELLIOTT R. MOFFET, of Joplin, in the county of Jasper and State of Missouri, have invented a new and useful

5 Improvement in Apparatus for Smelting and Calcining Lead and other Ores, of which the following is a full, clear, and exact description.

This invention relates to the treatment of 10 lead and other ores in which both a roasting or calcining furnace and a cupola-furnace are used; and it consists in causing the fumes from the roaster or calcining-furnace to be drawn or passed direct into the cupola-furnace; also, in causing the air which is supplied to the cupola-furnace to be heated by 15 the heat of or from the calcining-furnace. By this invention not only are the metallic substances or metals that pass off in the roasting or calcining of the ore saved, but also 20 much trouble and expense, as compared with the ordinary method or means, including dust-chambers and flues.

Reference is to be had to the accompanying 25 drawings, forming a part of this specification, in which similar letters of reference indicate corresponding parts in both the figures.

Figure 1 represents a front elevation of a 30 roaster or calcining-furnace and cupola-furnace combined, in illustration of my invention; and Fig. 2, a side elevation of the cupola-furnace, in part.

A indicates the calcining-furnace, and B the cupola-furnace combined, and C the floor 35 or ground line, which shows the calcining-furnace at a suitable elevation in relation to the cupola to secure the required action. The metals from both furnaces flow into a common kettle, D, the stack E of which is 40 made to inclose and keep warm by the heat within it the inclined spout F, that connects the kettle and roaster, and whereby the metal passing down said spout into the kettle is kept from chilling.

45 b b are the charging-doors of the cupola, and c the ash-pit of the kettle.

d is the flue forming a continuation of the stack F, for carrying off the smoke from the refining-kettle.

50 G is the smoke and fume chamber of the calcining-furnace, made of an enlarged ca-

pacity, with a downward branch, g, from one side of its upper end, connected with a suction-pan, H, that by a lower branch pipe, g', connects with suitable distributing pipes 55 and nozzles to the cupola-furnace, thus causing the fumes from the roaster or calcining-furnace to be drawn or passed direct into the cupola-furnace, as shown by arrows x.

I is the blower for supplying the air to the 60 furnaces—as, for instance, by a main pipe, h, into a stand-pipe, i, from which lower branch pipes, k, project, to pass the air into the roaster, and from the upper end of which a branch pipe, l, passes, to convey the air 65 warmed by the heat from the roaster or calcining-furnace to the cupola, the arrows y indicating the course or courses of the air.

Having thus fully described my invention, I claim as new and desire to secure by Letters 70 Patent—

1. The combination, with the calcining-furnace, the cupola, and the duct or ducts connecting said furnaces and arranged to pass the fumes direct from the calcining-furnace 75 to the cupola-furnace, of a suction device for thus passing said fumes from one furnace to the other, and a blower with connected ducts for supplying air to both furnaces, substantially as and for the purposes specified. 80

2. The combination, with the connected calcining and cupola furnaces, of the blower for supplying air to both furnaces, and pipes or ducts for conveying the air to the calcining-furnace, and for supplying air warmed by 85 heat derived from the calcining-furnace to the cupola-furnace, essentially as shown and described.

3. The combination, with the elevated calcining-furnace, cupola-furnace connected 90 therewith, and a refining-kettle common to both furnaces, of the spout for passing the metal from the calcining-furnace to the kettle and the stack of the kettle arranged to enclose said spout, whereby the metal passing 95 down said spout is prevented from being chilled, substantially as specified.

ELLIOTT R. MOFFET.
